Patented July 7, 1959

185,634

COMBINED OXYGEN TENT SUPPORT AND AIR CONDITIONING UNIT

Frank J. Fegan and William Harold Smith, Norwalk,
Conn., assignors to O.E.M. Corporation, East Norwalk,
Conn., a corporation of Connecticut

Application September 8, 1958, Serial No. 52,561

Term of patent 14 years

(Cl. D83—1)

Des. 185,634

PAGE 2

FIG. 5

FIG. 6

FIG. 7

Fig. 1 is a front elevational view of a combined oxygen tent support and air conditioning unit embodying our new design;

Fig. 2 is a left side elevational view thereof;

Fig. 3 is a rear elevational view thereof;

Fig. 4 is a right side elevational view thereof;

Fig. 5 is a fragmentary top perspective view of the front and left side thereof;

Fig. 6 is a fragmentary top perspective view of the rear and right side thereof; and

Fig. 7 is a fragmentary perspective view of the base thereof.

The bottom of the cabinet member is substantially plain.

We claim:

The ornamental design for a combined oxygen tent support and air conditioning unit, substantially as shown and described.
